(57) CLAIM

The ornamental design for a tactical belt, as shown and described.

DESCRIPTION

FIG. 1 is a top perspective view of the tactical belt showing my new design in a flat configuration;
FIG. 2 is a bottom perspective view thereof;
FIG. 3 is a top view thereof;
FIG. 4 is a bottom view thereof;
FIG. 5 is a side view thereof;
FIG. 6 is an opposite side view thereof;
FIG. 7 is a rear view thereof;
FIG. 8 is a front view thereof;
FIG. 9 is an enlarged detail view from FIG. 2;
FIG. 10 is an enlarged view of FIG. 7;
FIG. 11 is an enlarged view of FIG. 8;
FIG. 12 is a perspective view of the tactical belt of my new design with both ends connected to form a loop configuration;
FIG. 13 is a front view thereof;
FIG. 14 is a rear view thereof;
FIG. 15 is a first side view thereof;
FIG. 16 is a second side view thereof;
FIG. 17 is a top view thereof; and,
FIG. 18 is a bottom view thereof.

The tactical belt is shown in two configurations. The process and/or period in which the tactical belt transitions between these two configurations form(s) no part of the claimed design.

The tactical belt is shown with symbolic breaks in its length. The appearance of any portion of the article between the break lines forms no part of the claimed design.

The broken lines in the figures are for the purpose of illustrating portions of the tactical belt or an optional attachment ring and form no part of the claimed design.
